SPRING CUSHION CONSTRUCTION

Filed Sept. 13, 1937

UNITED STATES PATENT OFFICE

2,220,577

SPRING CUSHION CONSTRUCTION

Clarence H. Menge, Mount Clemens, Mich., assignor to The Murray Corporation of America, Detroit, Mich., a corporation of Delaware

Application September 13, 1937, Serial No. 163,564

6 Claims. (Cl. 155—179)

This application is a continuation in part of the co-pending application of Clarence H. Menge, Serial No. 44,697, filed October 12, 1935 which matured into Patent No. 2,116,402, issued May 3, 1938. The present invention relates generally to cushion construction. More particularly the present invention relates to resilient spring construction for use in cushions.

In order to obtain a full and complete understanding of the invention disclosed herein, reference may be had to the Kaden Patent No. 2,002,399, which relates specifically to the type of spring element used in connection with the present invention. Springs of the type disclosed in the Kaden patent are formed of a section of spring wire bent to a series of similar adjacent lateral convolutions all lying in substantially a single surface. In order to obtain maximum resiliency when using springs of this type, it is necessary that the elements as a whole be bent on an arc of relatively small radius and normalized to this curve. When the spring element is used, the element as a whole is tensioned until the arcuate shape thereof lies in an arc of substantially greater radius than when the spring is in normal condition in order that the resilience of the adjacent convolutions of the spring element will be supplemented by the resilience of the arcuate structure as a whole.

It is a general object of the present invention to provide a construction for a cushion embodying spring elements of the type disclosed in the Kaden patent referred to above.

A more particular object of the present invention consists in the provision of a cushion utilizing springs of the type shown in the Kaden patent which will be reversible and which have similar resilient surfaces on both sides thereof.

A further object of the present invention contemplates the provision of a cushion structure in which a single frame element is used for supporting the springs constituting the resilient surfaces on both sides of the cushion spring construction.

A further object of the present invention is to provide a cushion having resilient surfaces on both sides in which the elements forming the surfaces on the respective sides are disposed across the frame at substantially right angles to each other.

A further object is to provide a cushion construction having novel and advantageous uses which has one arcuate spring surface and an oppositely disposed arcuate spring surface in which

the arcs of the respective surfaces lie at right angles to each other.

Other objects of the invention will become apparent from the following specification, the drawing relating thereto, and from the claims 5 hereinafter set forth.

In the drawing in which like numerals are used to designate like parts in the several views throughout:

Figure 1 is a perspective view of a cushion construction embodying features of the present invention;

Fig. 2 is an enlarged fragmentary view showing the manner in which the terminal ends of the surface springs are secured in the border 15 wire of the cushion spring illustrated in Fig. 1;

Fig. 3 is a perspective view of a modified form of cushion construction embodying features of the present invention;

Fig. 4 is a side elevational view of the cushion 20 spring construction shown in Fig. 3;

Fig. 5 is an enlarged fragmentary perspective view illustrating the manner in which the terminal ends of the surface springs are secured in the border frame element in the structure illustrated in Figs. 3 and 4; and

Fig. 6 is a top plan view of the structure illustrated in Fig. 5.

Referring to the drawing and referring particularly to Figs. 1 and 2 an embodiment of the 30 present invention is illustrated in which a cushion is provided with a single marginal border wire element 10 which is substantially rectangular in shape. The border wire element 10 is substantially cylindrical in cross-section and has a continuous channel 12 cut therein throughout its length. This border-wire element preferably extends completely around and defines the marginal edge of the cushion construction. In order to maintain its rectangular form and rigidity, the 40 border wire frame element 10 is preferably supported by a brace element 14 which is preferably formed of relatively small gauge wire, and has its ends bent laterally and crimped into the channel of the border wire 10 on each side of the 45 frame.

A plurality of arcuate spring elements 16 have one-half of their last lateral convolutions crimped into the inwardly presenting channel 12 of the border wire element 10. These springs 16 constitute an arcuate spring surface on one side of the cushion; and a similar arcuate spring surface is provided on the other side of the cushion by means of a similar series of arcuate sinuous spring elements 18, each of which also has one- 55

half of its last lateral convolutions similarly crimped into the same inwardly presenting channel 12 of the border wire 10. This is shown in detail in Fig. 2.

5 In the embodiment illustrated in Figs. 1 and 2 the spring elements 16 and 18 extend in the same direction relative to the border frame 10 so that the curvature of the spring surfaces is substantially the same for both sides of the cushion.

10 This cushion construction is relatively simple to manufacture, and is highly resilient, due to the arcuate form of the spring elements 16 and 18. The spring elements 16 and 18 are preferably formed when manufactured to a curvature 15 of relatively small radius, and at the time they are imported into the border wire 10 they are tensioned to arcs of substantially greater radius in order that their inherent resiliency will thus be materially increased.

20 Referring to Figs. 3 to 6 a modified structure is illustrated in which curved spring surfaces are provided on the opposite sides of a single border frame member and in which the curvature of one of the spring surfaces is on an arc in one direction 25 across the frame member and the curvature of the other spring surface is on an arc at substantially a right angle to the arc of the first spring surface.

A border frame element 19 is provided which 30 is preferably substantially rectangular in shape and is preferably formed of sheet metal of rolled sections which may conveniently be formed in a continuous length. The border frame element 19 is generally of channel section and is provided 35 at substantially uniformly spaced points throughout its length with upraised portions 20 in the base thereof, which upright portions are preferably spaced apart from each other a distance slightly less than the transverse width of the 40 last lateral convolution of the spring element 16 which the channel is adapted to secure in position. The walls of the channel are crimped together at points 21 disposed substantially midway between the upraised portions 20 of the base 45 of the channel thus providing tunnels between these upraised portions which tunnels are adapted to receive and anchor the last lateral convolution of the spring elements in position within the channel.

50 In order to brace the border frame 19, transversely extending bracing elements 22 and 24 are provided which are arranged at right angles to each other and which have their respective ends anchored in the border frame element 19 in substantially the same manner as the spring elements 16 are anchored therein.

The spring elements 16 form one of the spring cushion surfaces and are so disposed that they provide a spring surface on an arc extending 60 across the frame in one direction. The spring elements 18 form the oppositely disposed spring surface and are so arranged as to provide a spring surface on an arc at substantially a right angle to the arc of the spring surface formed by the 65 elements 16. By so arranging the spring elements 16 and 18 relative to each other the cushion construction provided has advantageous uses in that the supporting surface formed by the elements 16 is properly positioned by the surface 70 formed by the elements 18.

The elements 16 and 18 are secured in the border frame element 19 in the same manner and the structure for so assembling the spring elements to the border frame element 19 has the advantages of ease and security of assembly.

The last lateral convolution of the spring elements 16 and 18 may be snapped into position between the upraised portions of the base of the channel having the convolution projecting through the tunnel formed by the crimped portion 21 of the channel. Thus it will be seen that when the seat cushion construction is assembled, it is merely necessary to snap the last lateral convolutions of the arcuate sinuous spring elements into position in these border frame elements; and due to the resiliency of the component parts, it will be seen that the spring elements will be firmly anchored in place. The upraised portions 20 of the channel base preclude longitudinal movement of the anchored convolution with respect to the channel and the crimped in portions preclude displacement of the convolutions with respect to the channel.

Formal changes may be made in the specific embodiments of the invention described without departing from the spirit and substance of the invention, the scope of which is commensurate with the appended claims.

What is claimed is:

1. In a cushion construction, a frame member 25 surrounding the marginal edge of the cushion and having an inwardly presenting channel section, and sinuous arcuate spring members having their ends anchored in said channel and forming resilient surface structures on both sides 30 of said cushion, the ends of the springs on the top and bottom side of the frame being oppositely disposed and substantially abutting.

2. In a cushion construction, a frame member surrounding the marginal edge of the cushion 35 and having an inwardly presenting channel section, and sinuous arcuate spring members having their ends anchored in said channel and forming resilient surfaces on both sides of said cushion, said spring members being aligned on 40 opposite sides of the frame and tensioned to lie along arcs of greater radius than that which they would normally assume with the ends of aligned spring oppositely disposed and substantially abutting.

3. In a cushion construction, a frame element extending around the marginal edge of said cushion, sinuous arcuate spring elements each having a portion of their last lateral convolutions anchored by said frame element and forming a 50 resilient surface structure on one side of the cushion, similar elements having their ends similarly anchored in said frame element and constituting an opposite surface structure for said cushion, said springs on opposite sides of the 55 frame being substantially aligned with their ends oppositely disposed and substantially abutting.

4. A cushion construction, having a spring surface and padding on both sides including, in combination, a frame element of inwardly presented channel section, strips of arched zig-zag springs on both sides of the frame having their ends secured in the channel along oppositely disposed edges of said frame and anchored thereto, the 65 ends of the springs on opposite sides of said frame being substantially aligned with the ends oppositely presenting and substantially abutting.

5. A cushion construction, having a spring surface and padding on both sides including, in combination, a frame element of inwardly presented channel sections, strips of arched zig-zag springs on both sides of the frame having their ends oppositely extended and secured in the channels along opposite disposed edges of said frame and 75

anchored thereto, and a brace extending across the opposite sides of said frame to provide strength thereto against deflection.

6. A cushion construction, having a spring surface and padding on both sides including, in combination, a frame element of inwardly presented channel sections, strips of arched zig-zag

springs on both sides of the frame having their ends secured in the channels along oppositely disposed edges of said frame and anchored thereto, the ends of said strips being substantially abutting in said channel to have said strips substantially aligned on opposite sides of said frame
